UNITED STATES PATENT OFFICE

WALTER J. BEATTIE, OF COHOES, NEW YORK, ASSIGNOR TO THE BEATTIE MANUFACTURING CO., OF COHOES, NEW YORK, A CORPORATION OF NEW YORK

CUFF AND METHOD OF MAKING THE SAME

Application filed May 25, 1929. Serial No. 365,958.

The present invention relates to apparel, and more particularly to a cuff for a shirt or the like and to the method of making the same.

An object of the invention is to provide a cuff of simple construction which may be manufactured and assembled with the garment by a minimum number of operations.

A further object of the invention is to provide a cuff which because of its construction may be manufactured by a comparatively few manual operations, the construction being of the character which will permit the use of automatic folding and turning machinery to a greater extent than has heretofore been possible.

Another object of the invention is to provide a cuff construction which is readily adapted for the reception of piping or other edge finishing means in the manufacture of the cuff, and which also may be readily attached to a shirt sleeve.

A characteristic feature of the invention is the utilization of a single blank of material for the outer faces or plies. The blank is folded or pleated transversely and the portions of the same at opposite sides of the pleat are arranged in facing relation with the pleat, and also one or more stiffening plies if desired, intervening, the pleat forming an open pocket adapted to receive the end of the sleeve or other portion of the garment to which the cuff or the like is to be attached.

Preferably, the edges of the blank are turned between the facing plies, the margins of which should coincide so that stitching adjacent the margins may secure together the two plies. In order that the ends of the pocket which receive the sleeve may be closed the folded edge of one ply extends over the pleat or fold, thereby closing the pocket at its ends.

Before sewing together the two plies, a suitable stiffening ply may be interposed, and if desired, it may be fitted beneath the folded-over edge of one of the plies and beneath the pleat. Moreover, a finishing edge for the cuff, such as piping, may be interposed between the free edges before the same are stitched together.

The foregoing and other objects and fea-

tures of the invention will become clearer as the description proceeds in connection with preferred embodiments disclosed in the accompanying drawings, wherein

Figure 1 is a plan view of a blank, the edges of which have been suitably folded or in-turned.

Figure 2 is a view on the line 2—2 of Fig. 1.

Figure 3 is a plan view of the blank during an intermediate stage of the pleat forming operation.

Figure 4 is a sectional view on the line 4—4 of Fig. 3.

Figure 5 is a fragmentary perspective view showing the folded blank with the edge of one ply about to be folded over the pleat to close one end of the pleat.

Figure 6 is a plan view of the cuff ready to be attached to a garment.

Figure 7 is a section on the line 7—7 of Fig. 6.

Figure 8 is a view similar to Fig. 7, showing the sleeve inserted in the pocket formed by the pleat.

Figure 9 is a perspective showing the cuff assembled with the garment.

Figure 10 is a fragmentary perspective showing one end of the pleat or pocket more clearly.

Figure 11 is a plan view of a modified form provided with piping as an edge finish.

Figure 12 is a sectional view on the line 12—12 of Fig. 11.

Figure 13 is a plan view of a fold-over cuff, otherwise of substantially the same construction as the form illustrated in Figs. 6 and 9.

Figure 14 is a sectional view on the line 14—14 of Fig. 13, and

Figure 15 is a sectional view of a fold-over cuff having a stiffener ply in the inner portion instead of the fold-over portion of the cuff.

Referring to the drawings for a more detailed description, 10 indicates a blank or piece of material, the edges of which may be in-turned or folded over one face of the blank. At the corners 12, the folded edges may be crimped to provide the desired curve, and a stiffener ply 13 may extend beneath one of the transverse folded edges 14 and the end folds 100

15 with its free or exposed edge 16 terminating at substantially the transverse center of the blank. The folded edges 14, 15 of the blank may be secured at spaced points, as by adhesive 17, which may be applied, if desired, by an appropriate mechanism which folds over the edge.

In order to form a pocket for receiving the end of a sleeve or the like, the blank is 10 pleated at substantially its transverse center, and to form such a suitable pleat, it may first be folded to the position illustrated in Fig. 4 to provide the center pleat fold 19 and one pleat-edge fold 20 which will constitute 15 one edge of an outer cuff ply 21. The other portion 22 of the blank at the opposite side of the pleat is then folded over upon the ply 21 in face to face relation therewith to provide a second ply with the pleat intervening or disposed between the two plies. 20 As will be observed, the stiffening ply 13 (Fig. 7) extends not only beneath the in-folded edge 14 of the ply 22, but also beneath the pleat and thus is held in position. 25 The pleat described provides an open pocket for the reception of a sleeve or the like, which may be stitched within the pocket, and in order to close the ends of the pocket, a folded edge 15 of one of the plies 21, 30 22 at each end of the pleat may be raised, as indicated in Fig. 5, to receive the pleat, and thereafter, the edge may be folded over the pleat (Fig. 10) thereby closing the ends of the pocket or pleat. To permit this operation, it is desirable to form in the blanks, cuts 35 24 (Fig. 1) which extend a short distance inwardly from each end of the blank.

To complete the cuff, it is simply necessary to stitch together the free marginal edges of 40 the two plies, as by stitching 25, and as will be noted (Fig. 6) the stitching terminates at points 25' so that the pleat or pocket is not sewed before insertion of the sleeve.

In order to assemble the completed cuff 45 with a sleeve S, the end 28 (Fig. 8) of the latter may be inserted into the pocket and secured therein by a transverse line of stitching 29 extending through the pleat, the end of the sleeve and through the two plies of the 50 cuff. This construction provides a cuff which may be readily applied to a garment simply by inserting the sleeve into the pleat or pocket. The free edge folds 20, 23 of the pleat provide finished cuff edges at opposite 55 sides of the sleeve, and it is, therefore, unnecessary for the operator when stitching the sleeve to the cuff to fold inwardly and secure the edges of the cuff plies. The center fold 19 of the pleat at the bottom of the pocket, 60 may abut the end of the garment sleeve, and thus by limiting the extent of insertion of the sleeve, insures an even positioning of the sleeve in the pocket. This is an important feature of the invention, since it is not necessary for the operator to exercise care in

attaching the cuff to the garment. It is simply necessary to project the sleeve into the cuff the full depth of the pocket, the bottom of which being straight insures a uniform insertion of the sleeve with little or no care on the part of the operator of the sewing machine which applies the stitching 29.

Referring to Figs. 11 and 12, the cuff shown corresponds to that of Fig. 6, except that piping 30, which comprises merely a strip of material folded upon itself, has its free edges inserted between the marginal edges of the plies 21', 22' and is secured by the marginal stitching 31, which unites the plies. This cuff also includes a stiffening ply 32, although, of course, the same may be dispensed with, as in the case of the cuff of Fig. 6, which does not require the stiffening ply 13.

In Figs. 13, 14 and 15, there is illustrated a cuff of the fold-over type, but otherwise of substantially the same construction as the cuff of Fig. 6. This cuff comprises a blank having a pleat with a center fold 33 and free edge folds 34, 35, the pleat forming a pocket 36, into which a sleeve or other part of a garment (not shown) may be inserted. And as will be understood, the blank is provided with the cuts 24 and the closed pocket ends illustrated in Figs. 5 and 10.

At opposite sides of the pocket, the two portions of the blank are arranged face to face to provide plies 37, 38, the inturned edges of which coincide and are secured together by marginal stitching 39. If desired, a stiffening ply 40 may be inserted beneath one folded-over edge and may have its free edge 40' terminating slightly short of the fold line 41 of the cuff (Fig. 14); this stiffening ply need not be included, as illustrated in Fig. 15. A stiffening ply 42 may have one edge inserted between the facing ply 37 of the cuff and the pleat, and may have its free edge 42' terminate adjacent the fold line 41 of the cuff. The stiffening ply may be extended throughout the cuff, should it be desirable to reinforce both portions of the same.

It will be understood that Figs. 14 and 15 illustrate slightly different forms, in that in Fig. 14 the stiffening ply is limited to the fold-over portion of the cuff, whereas in Fig. 15, the stiffener ply is limited to the inner portion of the cuff which has therein the pocket 36. In the latter form, the transverse line of stitching (not shown) which will be applied when the sleeve is inserted in the pocket 36, will be extended through the stiffener, as in the form of Fig. 8, to secure the stiffener in position.

Where reference is made in the specification or claims to a "shirt", it is to be understood that I intend to cover any article of apparel to which a cuff or the like is applied; and by the term "cuff" as used in the speci-

fication or claims, I intend to cover a collar or collar band as well.

Obviously, the invention is not limited to the precise details illustrated, and numerous 5 modifications may be made without departing from the invention, the essential features of which are set forth in the following claims.

I claim:

10 1. A shirt cuff comprising a piece of material transversely pleated intermediate its ends and having its portions on opposite sides of the pleat folded over the pleat and upon one another to form cuff plies, whereby the 15 pleat provides a transversely extending open pocket between the plies, and stitching securing together the plies, the edges of said plies being folded inwardly between the same with the folded edge of a ply at each end 20 of the pleat extending over the open end of the pleat whereby to close the pocket at its ends.

25 2. A shirt cuff comprising a blank having its free edges folded over the face of the blank, said blank being transversely pleated, the portions of the blank at opposite sides of the pleat being arranged face to face and forming facing plies with the pleat disposed therebetween and providing a marginal 30 pocket, the pleat at each end having an in-turned edge of one ply overlying the same and closing the end of the pocket, and stitching securing together the plies adjacent their marginal edges.

35 3. A shirt cuff comprising a blank having its free edges folded over the face of the blank, said blank being transversely pleated, the portions of the blank at opposite sides of the pleat being arranged face to face and 40 forming substantially coincident facing plies with the pleat disposed therebetween and providing a marginal pocket, the pleat at each end having an in-turned edge of one ply overlying the same and closing the end of the pocket, and stitching 45 securing together the plies adjacent their marginal edges.

45 4. A shirt cuff comprising a blank having its free edges folded over the face of the blank, said blank being transversely pleated, 50 the portions of the blank at opposite sides of the pleat being arranged face to face and forming facing plies with the pleat disposed therebetween and providing a marginal pocket, the pleat at each end having an in-turned edge of one ply overlying the same and closing the end of the pocket, stitching 55 securing together the plies adjacent their marginal edges, and the end of a sleeve secured in said pocket.

60 5. The improved method in the art of making cuffs which consists in folding over the marginal edges of a blank, transversely pleating the blank, disposing the portions of the same at opposite sides of the pleat in face to 65 face relation with the pleat intervening,

folding over each end of the pleat an inturned edge of one of the plies whereby to close the ends of the pleat, and stitching together the facing plies.

6. The improved method in the art of making cuffs which consists in folding over the marginal edges of a blank, transversely pleating the blank, disposing the portions of the same at opposite sides of the pleat in face to 70 face relation with the pleat intervening, folding over each end of the pleat an inturned edge of one of the plies, whereby to close the ends of the pleat, stitching together the facing plies, inserting the end of a sleeve to the pleat, and stitching the sleeve to the two walls 75 80 of the pleat.

In testimony whereof I have hereunto set my hand.

WALTER J. BEATTIE.
